ABSTRACT

For an apparatus for growing single crystals by the floating zone method, a pair of congruent prolate spheroidal reflectors for radiant energy are disposed outwardly of each other with their major axes aligned and with the distance between their axially inwardly disposed foci being less than the diameter of a molten zone placed at the location of these foci. A pair of congruent halogen lamps for supplying the radiant energy are held inside the respective spheroidal surfaces with their longitudinal axes parallel to the major axes and with the center of each lamp placed, apart from the axially outwardly disposed focus, less than a quarter of the longitudinal dimension of the lamps and a half of the transverse dimension thereof in the directions parallel and perpendicular to the major axes, respectively.

FIG. 5

APPARATUS FOR PRODUCING SINGLE CRYSTALS INCLUDING HALOGEN LAMPS ALIGNED WITH THE COMMON MAJOR AXES OF A SPHEROIDAL REFLECTOR PAIR

BACKGROUND OF THE INVENTION

This invention relates to an apparatus for growing single crystals by the floating zone method with radiant energy supplied from a pair of halogen lamps and concentrated onto the sample floating zone by a pair of inwardly reflecting, prolate spheroidal surface portions.

In Japanese Pat. application No. Syo 45-93,850 filed Oct. 23, 1970, and U.S. Pat. application Ser. No. 173,458 filed Aug. 20, 1971, an apparatus for heating a sample with concentrated radiant energy is described which comprises a pair of inwardly reflecting, substantially prolate spheroidal surface portions disposed outwardly of each other, said spheroidal surface portions having aligned major axes and a common focus, a source of radiant energy placed at one of the two foci of said spheroidal surface portions that are conjugate to said common focus, and means for holding a sample at the other of the two conjugate foci of said spheroidal surface portions. The sample may be typically a polycrystalline rod that is subjected to the floating zone method to be grown into a single crystal. In Japanese Pat. application No. Syo 45-95,371 filed Oct. 28, 1971, and the above-mentioned United States patent application, a similar apparatus is disclosed which further comprises a second, similar pair of prolate spheroidal surface portions disposed outwardly of each other and of the first-mentioned pair of spheroidal surface portions, one of the two foci of said second pair of spheroidal surface portions that are conjugate to the common focus of these spheroidal surface portions being placed at the above-mentioned other focus of the two conjugate foci of the first-mentioned pair of spheroidal surface portions, and a second source of radiant energy placed at the other of the two conjugate foci of said second pair of spheroidal surface portions. As described in the latter two applications, each source of radiant energy may be a helically wound filament of a halogen lamp disposed perpendicular to the aligned major axes.

In Japanese Pat. application No. Syo 45-82,438 filed Sept. 18, 1970, and a corresponding U.S. Pat. application Ser. No. 179,714, filed Sept. 13, 1971, an apparatus for producing a single crystal by the floating zone technique is disclosed which includes a heating device comprising a prolate spheroidal reflector and a halogen lamp placed at one focus of said reflector, the light emitted by said lamp being concentrated by said reflector at the other focus of said reflector and which is characterized in that said reflector has a ratio of the minor diameter to the major diameter in the range of 0.87 to 0.96 and that said apparatus further comprises a tube of a refractory material translucent for said light for accommodating the floating zone and its vicinity and for substantially defining a chamber together with said reflector and means for ventilating said chamber at a rate of at least once every 2 seconds.

The invention revealed in the first-mentioned three applications is directed to an apparatus whereby the radiant energy is concentrated on an image that is in the best possible congruency with the source or sources of radiant energy. It is, however, desirable to simplify the design of the apparatus and to lengthen the life of the

halogen lamp or lamps employed as the radiation source means. Furthermore, a restricted high temperature zone in the direction perpendicular to the aligned major axes should be provided in some applications, such as application to the floating zone technique. The primary object of the invention described in the latter-mentioned applications is to lengthen the life of the halogen lamp and to attain as uniform an azimuthal temperature distribution as possible around the crystal being grown. It is, however, desirable to further improve the azimuthal temperature distribution. In addition, the amount of the radiant energy concentrated at the sample must be increased in order to obtain a large single crystal and/or a single crystal of a higher melting point substance.

SUMMARY OF THE INVENTION

It is therefore an object of the present invention to provide an apparatus for growing single crystals by the floating zone method with concentrated radiant energy supplied from halogen lamps that is simple in design.

It is another object of this invention to provide an apparatus of the type described that enables a large amount of the radiant energy to be concentrated at the molten zone.

It is still another object of this invention to provide an apparatus of the type described that enables the radiant energy to be concentrated at the molten zone with restricted longitudinal distribution and with substantially uniform azimuthal distribution.

It is yet another object of this invention to provide an apparatus of the type described wherein the life of each radiant energy source means is an elongated halogen lamp.

According to the instant invention there is provided an apparatus for heating a molten zone with concentrated radiant energy including a pair of inwardly reflecting, substantially prolate spheroidal surface portions disposed outwardly of each other having their major axes substantially aligned with each other, and a pair of elongated sources of radiant energy wherein the improvement comprises:

means for holding said spheroidal surface portions in such a manner that the distance between the axially inwardly disposed foci of said spheroidal surfaces is less than the dimension of said sample in the direction of said aligned major axes;

means for holding said elongated sources of radiant energy (halogen lamps) inside said spheroidal surfaces, respectively, in such a manner that the longitudinal axes of said sources are substantially parallel to said aligned major axes, and that the center of each said source is spaced from the axially outwardly disposed focus of the associated spheroidal surfaces, by less than one quarter of the longitudinal dimension of the source when measured in a direction parallel to the aligned major axes and less than one half of the transverse dimension of the source when measured in the direction perpendicular to said aligned major axes and

means for holding said molten zone in a position such that said radiant energy converging toward at least one of said axially inwardly disposed foci is incident on the surface of said sample.

According to a preferred aspect of this invention, the apparatus further comprises a tube of a refractory material translucent for said radiant energy for accommo-

dating said molten zone and for substantially defining a chamber together with said spheroidal surface portions, said tube being disposed perpendicular to said aligned major axes, and still further comprises means for forcibly ventilating said chamber.

BRIEF DESCRIPTION OF THE DRAWINGS

For a more detailed understanding of the invention, reference may be had to the description below taken in conjunction with the accompanying drawings in which:

FIG. 1 is a schematic side view of an embodiment of the present invention, with the heating means shown in axial vertical section;

FIG. 2 shows the radiant energy distribution around a halogen lamp;

FIG. 3 shows the azimuthal energy distribution around the molten zone; and

FIGS. 4 and 5 are fragmentary axial vertical sectional views of modified holding means for the halogen lamps.

DESCRIPTION OF THE PREFERRED EMBODIMENTS

Referring to FIG. 1, an apparatus according to the present invention for growing a single crystal by the floating zone method comprises a pair of inwardly reflecting, substantially prolate spheroidal surface portions 1 and 1' disposed outwardly of each other and having mutually mating circular ends (not shown). The prolate spheroidal surfaces are preferably congruent and have substantially aligned major axes and a substantially common inwardly disposed focus F_1 or F_1' . The inwardly reflecting surfaces are preferably covered with gold either by plating or by evaporation with a view to raising the stability of the surfaces. Two elongated sources of radiant energy 2 and 2' are placed at the outwardly disposed foci F_2 and F_2' of the spheroidal surfaces which are conjugate to the substantially common focus F_1 or F_1' . Each of the sources 2 and 2' is preferably a quartz halogen lamp having a helically wound tungsten filament 3 or 3' and an accompanying power supply and holding means 4 or 4' and 5 or 5'. The filaments 3 and 3' are the actual sources of the radiant energy. As will be described in detail below, it has now unexpectedly been found that an appreciable increase in the heating capability and the desired distribution of the radiant energy around the substantially common focus F_1 or F_1' are achieved when the axes of the filaments 3 and 3' are held substantially parallel with the aligned major axes with the centers of the filaments 3 and 3' placed substantially at the respective foci F_2 and F_2' .

A seed crystal 11 is held by a lower chuck 12 attached to a vertical lower shaft 13. A rod of raw material or a polycrystalline rod 14 is similarly held by an upper chuck 15 attached to a substantially aligned vertical upper shaft 16. With the bottom surface of the polycrystalline rod 14 brought into contact with the top surface of the seed 11 and with the sources 2 and 2' excited, the abutting surface portions of the seed 11 and the rod 14 are heated by the radiant energy concentrated at the substantially common focus F_1 or F_1' to form a molten zone 17.

In the manner of the known floating zone technique and principles, the lower shaft 13 is rotatably and vertically slidably supported by a lower bearing means 21 and driven by a lower motor 22 through a pulley 23, a belt 24, and another pulley 25 as indicated by an arrow

100. Likewise, the upper shaft 16 is rotatably and vertically slidably supported by an upper bearing means 26 and driven by an upper motor 27 through a pulley 28, a belt 29, and another pulley 30 in the direction indicated by an arrow 101. Furthermore, the driving means for the lower and the upper shafts 13 and 16 are carried by a vertically movable support 31 having a female screw 32 engaging a male screw 33 that is driven through a reduction gear 34 by a feed motor 35 to feed 10 the support 31 very slowly along guide rails 36 and 36', with the sliders 37, 37', 37'', and 37''' of the support 31 sliding therealong. The rotation given to the molten zone 17 not only improves the azimuthal uniformity of heating but also provides the stirring action which in 15 turn improves the homogeneity of the composition within the molten zone 17. Except during the initial mounting of the seed 11 and the polycrystalline rod 14, the lower and the upper shafts 13 and 16 are carried by the support 31 with the relative position unchanged 20 and are fed downwardly relative to the heating means so that the molten zone 17 may travel upwardly relative to the polycrystalline rod 14 leaving the growing single crystal on the seed 11.

The apparatus further comprises a quartz tube 40 passing through the congruent spheroidal surface portions 1 and 1' adjacent to the mating ends. The tube 40 accommodates the molten zone 17 and its adjacent area and surrounds the adjacent end portions of the lower and the upper shafts 13 and 16. It is provided at the lower and the upper ends with a gas inlet 41 and a gas outlet 42, respectively. Sufficient clearances for the thermal expansion should be left between the tube 40 and the prolate spheroidal surface portions 1 and 1'. The tube 40 and the prolate spheroidal surface portions 1 and 1' thus define a substantially annular chamber. The apparatus further comprises pipes 51, 52, 53, and 54 for ventilating the chamber and ducts 61 and 61' for cooling the prolate spheroidal reflectors 1 and 1'.

Referring to FIG. 2 wherein the abscissa represents the angle θ schematically shown therein for a halogen lamp and the ordinate represents the relative radiation energy in percentage, it is understood that most of the radiant energy is directed within a certain solid angle formed on both sides of a plane bisecting the length of the filament. It follows therefore that in an apparatus of the kind wherein the elongate radiant energy sources are disposed perpendicular to the aligned major axes, an appreciable amount of the radiant energy is directed within a solid angle subtended by the mating ends of the prolate spheroidal surface portions 1 and 1' without being concentrated at the substantially common focus F_1 or F_1' . In accordance with the instant invention, the loss of radiant energy is reduced to a minimum to strengthen the heating capability.

With two 2-kW quartz halogen lamps disposed parallel to the aligned major axes, the radiant energy concentrated at a cylindrical sample of 10 mm in diameter was 1,950 W (49 percent). With two similar lamps disposed perpendicular to the aligned major axes and to the sample, the above-mentioned radiant energy was 1,700 W (43 percent). With one similar lamp used in the apparatus described in the aforesaid latter applications, the above-mentioned radiant energy was 1,420 W (71 percent). In this connection, it should be pointed out that the quartz tube 40 absorbs about 10 percent of the radiant energy incident thereon. At any rate, it is possible with the instant invention to increase

the amount of the radiant energy concentrated at the sample although the highest efficiency is attainable with the one-prolate-spheroidal-reflector apparatus due to the fact that almost all radiant energy emitted by the radiant energy source placed at one of the foci is concentrated at the other focus. It is thus possible with an apparatus according to this invention to grow a single crystal as large as 15 mm in diameter of a manganese-zinc ferrite whose melting point is 1,650° C while the maximum diameter of the crystal grown by the one-prolate-spheroidal-reflector apparatus is 12 mm. Furthermore, it is possible with an apparatus according to this invention to melt a rod of 10 mm in diameter of calcium titanate having the melting point of 1,915° C.

Referring to FIG. 3 wherein the abscissa represents the azimuth around the cylindrical molten zone 17, a solid-line curve 71 shows the relative radiant energy incident on the peripheral surface of the molten zone 17 as simulated by an electronic computer with respect to an apparatus in accordance with the present invention. A dashed-line curve 72 illustrates the similar energy as likewise simulated in respect of a one-prolate-spheroidal-reflector apparatus. The latter-mentioned apparatus gives rise to an azimuthally periodic temperature variation of as much as $\pm 0.6^\circ$ C in the molten zone 17 even though the zone 17 is rotated at a rate of 30 RPM. With an apparatus according to this invention, it is possible to reduce the temperature variation to $\pm 0.1^\circ$ C at most with the molten zone 17 rotated at 30 RPM.

Simulation by means of an electronic computer has further revealed that the total amount of the radiant energy incident on the molten zone and the azimuthal distribution of such energy is nevertheless acceptable even if the distance between the closely spaced foci F_1 and F_1' is less than the dimension of the molten zone in the direction of the aligned major axes and if the center of each elongated halogen lamp is spaced from the focus F_2 or F_2' by an amount less than a quarter of the longitudinal dimension of the lamp, or more exactly, the length of filament coil in the direction parallel with the aligned major axes and less than a half of the diameter of the source in the direction perpendicular to the aligned major axes. The center of the halogen lamp may be displaced either inwardly or outwardly relative to the focus F_2 or F_2' in the direction parallel to the aligned major axes. Similarly, the center of the halogen lamp may be displaced relative to the focus F_2 or F_2' along a plane perpendicular to the aligned major axes.

The ventilating means serves to keep the quartz tubes of the halogen lamps 2 and 2' within the desired temperature range of 200° C through 1,000° C. Otherwise, the filaments 3 and 3' will snap within several minutes after being switched on due to the disturbance caused to the halogen cycle because the quartz tubes of the lamps 2 and 2' are heated above 1,300° C on account of the additional heating resulting from the radiant energy concentrated back from the molten zone 17 at the halogen lamps 2 and 2'. It is thus possible to keep the quartz tubes of the lamps 2 and 2' at about 300° C and to lengthen the life to about 100 hours by pumping the air at 1×10^4 litres an hour into or out of the above-mentioned chamber of the volume of about six liters through the pipes 51, 52, 53, and 54. Substitution of an inactive gas, such as nitrogen, for the air attains an additional advantage of preventing oxidation of the re-

flecting surfaces. The gas may be pumped into and out of the chamber through some of the pipes 51, 52, 53, and 54 and the remaining pipes, respectively. In this connection, it is to be noted that localized cooling of the quartz tubes of the lamps 2 and 2', which may be effected by blowing the gas directly against the halogen lamps 2 and 2', is not desirable because of the adverse effect caused thereby to the halogen cycle.

Referring finally to FIGS. 4 and 5, the power supply 10 and holding means 4 or 4' which extends near to the tube 40 may be formed into the shapes depicted therein. In any event, these supply and holding means are subjected to the heat from the halogen lamp and the molten zone 17 and should consequently be made 15 of a refractory material. With the arrangement shown in FIG. 1, it is possible to effectively cool the power supply and holding means 4 and 4' by circulating cooling water therethrough as symbolically depicted by an arrow 102.

With the apparatus illustrated with reference to FIG. 1, about a half of the energy emitted by the halogen lamps 2 and 2' is absorbed by the molten zone 17, the seed 11, and the polycrystalline rod 14. An appreciable amount of the absorbed energy is reradiated from the 20 vicinity of the molten zone 17. Most of the reradiated energy and the other half of the energy emitted by the halogen lamps 2 and 2' is absorbed by the prolate spheroidal surface portions 1 and 1' while it is repeatedly reflected, thus raising the temperature thereof. The 25 ducts 61 are provided and 61' for a coolant, such as water to, prevent the prolate spheroidal surface portions 1 and 1' from being oxidized by the otherwise excessively raised temperature this would cause a reduction in reflecting power.

Incidentally, it is possible to leave a gap between the adjacent ends of the prolate spheroidal surface portions 1 and 1'. The tube 40 for accommodating the molten zone may be made of any refractory material that is translucent to the radiant energy. It will be understood by those skilled in the art that numerous variations and modifications of the embodiments disclosed above are possible. However, the scope of the invention is defined by the following claims only and not by the description above.

We claim:

1. An apparatus for growing single crystals with radiant energy supplied from a pair of elongated halogen lamps and concentrated by cooperation of a pair of inwardly reflecting, substantially prolate spheroidal surface portions disposed outwardly of each other having their major axes substantially aligned with each other, wherein the improvement comprises:

means for holding said spheroidal surface portions in such a manner that the distance between the axially inwardly disposed foci of said spheroidal surfaces is less than the dimension of said molten zone in the direction of said aligned major axes;

means for holding said lamps inside said spheroidal surfaces, respectively, in such a manner that the longitudinal axes of said lamps are substantially parallel to said aligned major axes, and that the center of each said lamp is spaced from the axially outwardly disposed focus of the associated surfaces by less than one quarter of the longitudinal dimension of the lamp when measured in an inward or outward direction parallel to the aligned major axes and less than one-half of the transverse dimen-

sion of the lamp when measured along a plane perpendicular to said aligned major axes from said aligned major axes; and means for holding said molten zone in a position such that said radiant energy converging toward at least one of said axially inwardly disposed foci is incident on the surface of said molten zone.

2. The apparatus as claimed in claim 1, further comprising:

a tube of a refractory material that is translucent with respect to said radiant energy for accommodating said molten zone and for substantially defining a chamber together with said spheroidal surface portions, said tube being disposed perpendicular to

said aligned major axes; and means for forcibly ventilating said chamber.

3. The apparatus as claimed in claim 2, wherein said ventilating means comprises means for introducing gas into said chamber.

4. The apparatus as claimed in claim 2, wherein said ventilating means comprises means for sucking gas out of said chamber.

5. The apparatus as claimed in claim 1, wherein said 10 spheroidal surface portions are substantially congruent and said lamps are substantially congruent.

6. The apparatus as claimed in claim 5, wherein said spheroidal surface portions have common mating ends.
